UNITED STATES PATENT OFFICE.

FRANCIS L. CLARK, OF LEE'S SUMMIT, MISSOURI.

SEWING-MACHINE MOTOR.

SPECIFICATION forming part of Letters Patent No. 446,964, dated February 24, 1891.

Application filed June 27, 1890. Serial No. 356,964. (No model.)

To all whom it may concern:

Be it known that I, FRANCIS L. CLARK, a citizen of the United States, residing at Lee's Summit, in the county of Jackson and State 5 of Missouri, have invented a new and useful Sewing-Machine Motor, of which the following is a specification.

This invention has relation to improvements in connecting-rods for steam-engines, sewing-machines, lathes, and other machinery employing a fly-wheel, and also to improvements in such wheels.

The objects of the invention are to provide such a connection between the connecting-rod leading from the motive power to the fly-wheel as will avoid any dead-centers and be adapted for immediate starting in the proper direction the instant power is applied and without any preliminary starting by hand by 20 the operator or otherwise.

I have herein illustrated the device as connecting the treadle and fly-wheel of an ordinary sewing-machine; but, as will be apparent from the above and the subsequent description, the invention may be applied to the various types of machinery heretofore enumerated and others too numerous to mention.

With the above objects in view the invention 30 consists in certain features of construction hereinafter specified, and particularly pointed out in the claim.

Referring to the drawings, Figure 1 is a side elevation of a sewing-machine supporting 35 standard, a fly-wheel and treadle, and connections in accordance with my invention. Fig. 2 is a similar view, the hub or rear of the treadle being depressed. Fig. 3 is a detail in perspective of one of the clutch arms or levers. Fig. 4 is a transverse section through the wheel. Fig. 5 is an enlarged elevation in detail of the fly-wheel and clutch-levers. Fig. 40 6 is a detail of the upper ends of the connecting-rods.

Like numerals of reference indicate like parts in all the figures of the drawings.

1 represents the sewing-machine standard, of the usual construction and provided with the usual treadle-rod 2, upon which is pivoted 45 the foot-treadle 3, the same being pivoted upon the rod near its center. The standard

is also provided with an inwardly-disposed stub-shaft 4, upon which is mounted for rotation the usual grooved band and fly wheel 5. The fly-wheel 5 is of the ordinary construction, with the exception that the inner face of the same is provided with an annular collar 6, extending inward therefrom, said collar being concentric with the stub-shaft 4, upon which is loosely mounted a pair of levers 7 and 8. The lever 7 is extended at both sides of its pivot, its longest end occurring close to the inner wall of the collar 6 and its shortest end being pivotally connected, as at 9, to the upper end of a connecting-rod 10, 60 the lower end of the rod being pivotally connected to the rear end of the treadle 3 or leading to any other motive power, as will be readily understood by those conversant with engines and kindred mechanisms. The lever 70 8, like its companion, terminates close to the inner wall of the collar, and about midway its length, or between its pivot and its outer end, is pivotally connected, as at 12, to a short connecting-rod 13, the lower end of which is 75 hinged, as at 14, to the connecting-rod 10, near its middle. The two rods 10 and 13 have their adjacent inner faces or edges slightly cut away, so as to enable them to receive or embrace the end of the stub-shaft; 80 and the upper end of the longest connecting-rod 10 has its adjacent edge provided with a buffer or stop 15. From this construction it will be apparent that when the hub or rear part of the foot-treadle is raised and the connecting-rods lowered the free end of the 85 clutch-lever 7 will be raised and the similar end of the shortest clutch-lever 8 will be lowered, and when the hub or rear part of the treadle is depressed said levers assume an 90 opposite relative position, so that as one lever is being lowered the other is being raised, and, supposing said levers to have frictional contact with the inner wall of the collar only during the time they are being raised, it will 95 be apparent that the fly-wheel will be given a constant and uninterrupted rotary motion.

Numerous frictional devices will readily suggest themselves, and I have herein shown one of the many expedients, which I will now 100 proceed to describe. The ends of the levers 7 and 8 are provided with recesses 16, of ob-

long shape, and inclined bottoms 17, and in each of said recesses there is mounted a loose ball 18. The diameter of the ball is such that when at the top of the recess, as when the levers 5 are returning to a lowered position, they ride lightly over the inner wall of the collar 6, and when said levers are rising they become jammed between the wall of the collar and the shallow portion of the bottom of the recess, and thus form a rigid driving connection between said lever and the collar. It will also be apparent that the relative proportion of the connecting-rods is such that the clutch-levers are never raised or lowered 10 to such a height as to form in connection with said rods a dead-center. The buffer or stop will at all times prevent such an event, so that the machine may be started in the proper direction, regardless of the point of 15 rest at which the levers may be located, and the motion is continuous and uninterrupted.

Having thus described my invention, what I claim is—

The combination, with a fly-wheel, a shaft for the same, and a collar arranged at one 25 side of the wheel and concentric with the shaft, of a pair of clutch-levers, one of which is extended at one side of its pivot and both of which are loosely mounted on the shaft, a connecting-rod pivoted to the extension of one 30 of said levers and means for operating the rod, a shorter connecting-rod pivoted to the companion lever and hinged to the first-mentioned rod, and a stop or buffer arranged at the upper end of the first-mentioned connecting-rod and adapted for contact with the opposite rod, thereby limiting the separation of the clutch-levers, substantially as specified.

In testimony that I claim the foregoing as my own I have hereto affixed my signature in 35 presence of two witnesses.

FRANCIS L. CLARK.
